MICROPHONE

Burt E. Schell, Jr., Evanston, Ill., assignor to
Shure Brothers, Incorporated, Chicago, Ill., a
corporation of Illinois

Application August 19, 1949, Serial No. 4,607

Term of patent 14 years

(Cl. D26—14)

To all whom it may concern:

Be it known that I, Burt E. Schell, Jr., a citizen of the United States, residing at Evanston, in the county of Cook and State of Illinois, have invented a new, original, and ornamental Design for a Microphone, of which the following is a specification, reference being had to the accompanying drawings, forming a part thereof, in which:

Figure 1 is a perspective view of a microphone embodying my new design;

Fig. 2 is a front elevational view thereof on a somewhat larger scale;

Fig. 3 is a side elevational view thereof on the same scale as Fig. 2, and

Fig. 4 is a top plan view thereof on the same scales as Figs. 2 and 3.

I claim:

The ornamental design for a microphone, substantially as shown.

BURT E. SCHELL, JR.
